UNITED STATES PATENT OFFICE.

BRUCE WALTER, OF PITTSBURGH, PENNSYLVANIA, ASSIGNOR OF ONE-HALF TO
GEORGE H. SMITH, OF ASPINWALL, PENNSYLVANIA.

GAS-CLEANER.

1,074,913.

Specification of Letters Patent.

Patented Oct. 7, 1913.

Application filed February 8, 1909. Serial No. 476,613.

To all whom it may concern:

Be it known that I, BRUCE WALTER, a citizen of the United States, residing at Pittsburgh, in the State of Pennsylvania, have 5 invented certain new and useful Improvements in Gas-Cleaners, of which the following is a specification.

My invention relates to devices for cleaning gases particularly by contact with water, 10 and its primary object is to provide a more efficient cleaner in which the gas is brought into intimate contact with cold water without being required to take up vapor or free moisture, and to prevent the accumulation 15 of dirt on the surface of the water, etc.

I have illustrated the invention in a simple form in the accompanying drawing, wherein—

Figure 1 is a side elevation of my device; 20 Fig. 2 is a section on the line (2) in Fig. 1; Fig. 3 is an enlarged cross-section of a convenient form of water feeding pipe and Fig. 4 is a partial side elevation of the same.

Heretofore gas cleaning devices have been 25 used in which particles of dirt were taken out by forcing the gas into violent collision with a body of water, but in this case the water soon becomes covered with a scum and its efficiency has been destroyed. There have 30 also been devices in which running water was used and the gas forced through cascades of water, etc., or sprayed into the body of gas; in such cases the gas necessarily took up large quantities of vapor and free moisture 35 and the whole apparatus was complicated and expensive.

Generally speaking, the main idea of my device is to pass the gas over a smooth surface of running water and immediately 40 move the water out of the way.

Various other advantages will hereinafter appear.

As seen in the drawing, I provide a large 45 casing 5 into which the gas enters at the top by a pipe 6 and escapes at the bottom by pipe 7. This is preferably rectangular and may conveniently be made open from side to side for more efficient cooling by air circulation, and as shown it is built of joined partitions 8, 9, and 10 connecting the two sides of the casing and made gas-tight, so that they 50 collectively provide a series of inclined passages 11 as shown in Fig. 2. That is, the inner construction is such that the entering

gas first impinges on inclined plate 9 and 55 thence passes down through the vertical spaces 12 and impinging again and thence suddenly turning and inclining upwardly over the next inclined partition 9^a, and so forth. The upper surfaces of the plates 60 forming the inclined passages are covered by a thin smooth sheet of flowing water, fed in by slotted pipes 13, which may all be conveniently made as branches of a main pipe 14 as shown in Fig. 1. These pipes have 65 small slots lying flush with the upper surface of the plates 9 and project a sheet of water down the incline and into troughs 15. These troughs are inclined and the water 70 flows out of them into discharge pipes 16 which preferably are independent and all empty into a receiving reservoir 17 some distance below the surface. It will be noted that the troughs 15 and all the passages are sealed so that the water outlet is also a gas 75 seal. For more efficient cooling I may also employ spray pipes for projecting water on the outside surfaces of the inclined passages, as indicated at 27. I preferably use for the pipes 13 a construction such as shown in 80 Figs. 3 and 4, where the conduit is made of a main body 18 having a cylindrical section and an upper neck 19 covered by plate 20. Just under the plate 20 there is a series of elongated slots 21 for egress of the water, 85 and in these slots I provide a series of cleaning fingers 22 supported on bars 23 which are parts of a spider attached to shaft 24. The spider and the fingers of course slide 90] freely and at the outer end the rod 24 is provided with a handle 25 for operating it, and of course this rod makes a water tight joint with the end of the pipe 13, by means of packing box 26. By manipulating the handle 25, the cleaning fingers 22 can be slid 95 back and forth in the slots of the water feeding pipe to keep it open and clean.

It will be seen by this construction that the gas frequently changes direction and passes many times in upwardly slanting 100 passages in intimate contact with large areas of smooth water surface, and that this water surface in the meanwhile is constantly renewed so that it is constantly clean and cool; the dirt being carried away at once. Also as 105 the gas becomes cooler in its downward passage it continually meets with new surfaces of cold water. Moreover, the water, after

washing the gas is immediately carried off, so that the gas is never in contact with dirty water. The gas in passing up through the passages 11 against the friction of water moving in the opposite direction, will attain a rolling motion, and this facilitates the precipitation of dirt because it brings every part of the gas into contact with the water, and moreover, by striking the surface 10 more directly projects the dirt particles beneath the surface. By reason of the washing surfaces being inclined and covered by running water, while the water outlet troughs also are inclined, it will be noted that I entirely avoid any pockets or places 15 where dirt can collect in the washer.

I claim—

1. A gas cleaner comprising a casing having a continuous series of unobstructed gas 20 passages placed one above another in zig-zag fashion and having inclined surfaces, means for providing on said surfaces a constantly flowing sheet of water in contact with the gas and flowing in opposite direction to the movement of the gas, and means 25 for carrying off the water from each inclined surface independently.

2. A gas cleaner comprising a casing provided with a continuous series of zig-zag 30 passages vertically arranged therein and forming an unobstructed passage for gas, means supplying a sheet of water on the bottom of each passage entirely below the gas therein and an outlet carrying off the 35 water from each of said inclined surfaces

immediately and independently, substantially as described.

3. A gas cleaner comprising a casing having a zig-zag gas passage from top to bottom and composed of upwardly inclined 40 passages in series in zig-zag fashion, means for continually supplying a sheet of the water on the bottoms of each of said inclined passages and extending at its lower end out of the zone of the flowing gas and 45 a gas tight passage and discharge receptacle for the water on each one of said surfaces, substantially as described.

4. In a gas cleaner, the combination with an inclined plate forming part of a gas 50 passage, a water seal outlet from the same, and a supply pipe adapted to feed a sheet of water on the plate, the said pipe having a narrow slit outlet for the water, and means to clean the said outlet without interrupting 55 the flow of water.

5. A gas cleaner comprising a casing having unobstructed gas passages formed by inclined plates having each an independent means to drain water therefrom said casing 60 being open to admit free circulation of air under the surface of the gas passage.

In testimony whereof I have hereunto signed my name in the presence of the two subscribed witnesses.

BRUCE WALTER.
